UNITED STATES PATENT OFFICE

2,458,852

ROLL TENSION DEVICE

Sigurd H. Helland, Whitinsville, Mass., assignor
to Whitin Machine Works, Whitinsville, Mass.,
a corporation of Massachusetts

Application May 31, 1946, Serial No. 673,558

3 Claims. (Cl. 19—135)

1

This invention relates to combers and other similar machines in which textile fibers are drafted between tensioned drawing rolls.

It is the general object of my present invention to provide improvements in the devices for applying spring tension to the pairs of drawing rolls, and to provide an improved construction for relieving such tension when desired.

To the accomplishment of these objects, I provide improved means for separately supporting and guiding the springs which apply tension to each top drawing roll, and I also provide improved means for applying a lifting and pressure-relieving force to the collective tension devices of a set of drawing rolls.

My invention further relates to arrangements and combinations of parts which will be herein-after described and more particularly pointed out in the appended claims.

A preferred form of the invention is shown in the drawings, in which

Fig. 1 is a sectional side elevation of a set of drawing rolls having my improvements applied thereto;

Fig. 2 is a detail sectional end elevation, taken along the line 2—2 in Fig. 1;

Fig. 3 is a sectional front elevation, taken along the line 3—3 in Fig. 1; and

Fig. 4 is a partial sectional view, similar to Fig. 3 but showing the parts in a different operative relation.

Referring to the drawings, I have shown parts of a commercial combing machine comprising a frame 10 on which a box-like casing 11 is secured by bolts 12. Side rails 14 are mounted on the casing 11 and are secured thereto by bolts 15. The upper surfaces of the rails 14 are grooved longitudinally as shown at 16 in Fig. 3 to receive and guide the bearing boxes 20 in which the bottom rolls B are rotatably mounted and in which the bearings 22 for the top rolls R are vertically adjustable. The rails 14 are longitudinally slotted to receive bolts 24 by which the bearing boxes 20 are held in desired spaced relation along the rails 14.

A cross bar 30 is provided for each pair of drawing rolls and is provided with end openings 31 (Fig. 3) to receive the bolts 24 which thus act to clamp both a bearing box 20 and an associated cross bar 30 to a side rail 14. Correct relative alignment of these parts is thus maintained.

Tension is applied to each top roll R by springs S acting through rods 40 and links 41. Each rod 40 extends downward loosely through a guide-sleeve 44, and receives the downward spring pressure against a washer 45 and collar 46, the

2

spring tension devices being of the usual construction. At its upper end, each sleeve 44 engages a cross bar 30, and each rod 40 extends through a longitudinal slot 48 in said cross bar.

A cross arm 50 is mounted above each cross bar 30 and is slotted at its ends to receive the spring-tensioned rods 40. Washers 51 on the rods 40 engage the upper end surfaces of the cross bar 50. A stud 54 is fixed at the middle of each cross arm 50 and extends freely downward through a guide-opening in a lug 55 formed on the under side of the associated cross-bar 30.

The studs 54 for a full set of drawing rolls all engage the upper side of a shelf 60 which is pivoted at 61 to the ends of the casing 11. A cam shaft 65 (Fig. 1) is mounted in bearings in the casing 11 and is provided with eccentrics 66 which engage the under side of the shelf 60. A handle 70 at one end of the cam shaft 65 provides for convenient manual operation thereof.

By shifting the eccentrics 66 from the inoperative position shown in Fig. 3 to the operative position shown in Fig. 4, the spring tension on all of the top rolls R of a set of drawing rolls may be simultaneously relieved, which is desirable when top rolls having cushioned surfaces are to be inoperative for a considerable period.

The provision of a cross bar 30 and cross arm 50 for each pair of drawing rolls, and the provision of means for holding these parts in accurate alignment with the corresponding roll bearing boxes permit convenient transverse adjustment of the drawing rolls to meet drafting conditions, while at the same time the associated tension devices are maintained in accurate alignment.

The provision of the swinging shelf between the eccentrics 66 and the studs 54 permits application of a more directly vertical relieving pressure to the studs 54, so that any tendency to bind is avoided.

Having thus described my invention and the advantages thereof, I do not wish to be limited to the details herein disclosed, otherwise than as set forth in the claims, but what I claim is:

1. In a drawing mechanism having pairs of drawing rolls, bearing boxes for said rolls and side rails along which said boxes are adjustable, in combination, a cross bar for each pair of drawing rolls, a bolt extending through each end of each cross bar and through the adjacent side rail and into the adjacent bearing box and clamping said three parts together, with said cross bar and said bearing box in permanent assembled alignment, and spring tensioning means for each pair of rolls positioned and guided by the associated

cross bar and shiftable therewith along said rails.

2. In a drawing mechanism having pairs of drawing rolls each comprising a top roll and a bottom roll, bearing boxes for said rolls and side rails along which said boxes are adjustable, in combination, a cross bar for each pair of drawing rolls, means to secure said cross bar to said rails in alignment with said bearing boxes, spring means to tension said top rolls, a cross arm operable to relieve the spring tension on the associated top roll, a guiding stud in said cross arm slideable in said cross bar, and means to engage said stud and lift said cross arm to relieve the spring tension.

3. The combination in a drawing mechanism as set forth in claim 2, and in which the lifting

means comprises a shelf pivoted to swing about a laterally offset horizontal axis and engaging the lower ends of a plurality of said studs, and cam means to raise said shelf.

SIGURD H. HELLAND.
